UNITED STATES PATENT OFFICE

CORNELIUS J. CURRIER, OF SALEM, MASSACHUSETTS, ASSIGNOR TO ALVAH P. THOMPSON, OF SALEM, MASSACHUSETTS

CLIP

Application filed September 6, 1932. Serial No. 631,839.

This invention relates to improved clips, particularly for holding sheet articles such as leather hides upon a supporting screen, board or rack.

5 It has heretofore been common to secure hides which are being dried or which have been tanned upon boards by tacks driven through the edge portions of the screen into the supporting board. More recently drying 10 apparatus has been devised in the form of an open frame with toggles or clamps secured to the edges of the skin and connected to the frame by strings or engaging a wire mesh screen supported by the frame. For 15 example, Patent No. 1,372,337 to C. W. Cass and W. L. Baxter discloses such an arrangement and illustrates typical toggles which have been employed for this purpose. These 20 toggles or clamps have been relatively expensive, and due to the necessarily firm gripping engagement of the edge of the skin by the jaws of the clamp, they have damaged numerous localized areas at the edge of the skin.

The present invention affords a clip which 25 may be employed either with a supporting board, or a frame having string attachments or a meshed screen. My clip engages the extreme edge portion of a hide or skin while imparting less damage to the margin of the 30 skin than necessarily results from the employment of the conventional jaw type clamps or toggles. To permit these desirable results, I provide a clip in the form of a sheet metal member having a body portion adapted to be 35 hooked onto or secured to the supporting screen frame or board and an integral outstanding flange having an upstanding prong or prongs to penetrate the extreme edge of the hide, the hide being drawn taut so that 40 it engages the edge of the outstanding flange with a snubbing action, thus affording a relatively firm grip. At the upper end of the clip I may provide a bent portion to afford a finger hold to permit the more ready connection 45 of the clip to the supporting screen or the like.

In the accompanying drawing:

Fig. 1 is an elevational detail showing the arrangement of my improved clips when 50 supporting a hide upon a meshed screen;

Fig. 2 is a section indicated by line 2-2 of Fig. 1;

Fig. 3 is a front elevation of one form of clip;

Fig. 4 is a similar view of an optional 55 form of clip;

Fig. 5 is a top view of the clip shown in Figs. 1 to 3; and

Fig. 6 is a sectional view similar to Fig. 2, but showing the arrangement of the clip when 60 secured to a supporting board or plank.

In the accompanying drawing, the numeral 1 designates a support for the hide to be dried in the form of a wire screen, although a perforated plate or other suitable 65 structure may be employed as long as numerous closely spaced recesses or openings are provided to engage the clip 2, which more particularly forms the subject matter of the present invention. This clip, as shown more 70 clearly in Figs. 2 and 3, may comprise an integral strip of sheet metal having a substantially planar body portion 4 from which a rearwardly extending tab or prong 7 is struck 75 out to hook over a portion of the wire mesh 1 or the like, as shown in Fig. 2. The lower end of the clip is in the form of a flange 6, bent out substantially at right angles to the body portion 4 and providing a substantially straight edge 5. The prongs 9 are inclined 80 upwardly from the flange 6 and inclined inwardly toward the body portion 4.

The sheet metal at the upper end of the clip 2 may be bent over in substantially the form of a semi-cylindrical extension 16 to afford a 85 finger hold.

In use, clips of this character are secured to a hide, as the hide 10, by penetrating the edge portion of the hide by the pointed prongs 9 (see Fig. 2) and the hooks or tabs 7 are then 90 engaged with portions of the support 1 so that the body portion of the hide is drawn taut between the edges 5 of the supporting clips. Thus each edge 5 has a firm frictional engagement with the marginal portion of the 95 hide in addition to the penetrative engagement of the prong 9 with the extreme edge of the hide, and a singularly firm engagement of the hide with the clip is assured.

Fig. 4 illustrates a modified embodiment 100

of the invention provided with a single centrally disposed prong 9^a in the place of the two prongs 9 shown in Figs. 1, 2 and 3.

As shown in Fig. 5, a clip 2^a of this general character may be employed when a board is used rather than a meshed screen or the like for a support. As shown, the prong 7^a may be relatively sharp and driven into the wooden body of the board 12, thus firmly to support the clip. If desired, suitable strings can be looped about the prongs 7 of clips of the type shown herein to support the hide by means of string attachments upon a frame.

It is evident that a clip of the type disclosed herein may be manufactured out of sheet metal stock at a very low cost and that it is adapted to provide a relatively firm engagement with the edge of the hide without injuring any substantial area of the same, since the edge 5 of the flange 6 has considerable length and does not dig into the hide to the same extent as is the case with the jaw-type clamps or toggles. In other words the mark in the leather made by the edge 5 is more easily removed than the impression of a conventional jaw toggle; accordingly, despite the small openings made by the prongs 9 of my clips in the leather, the latter is actually injured less than by the clamps previously used. Furthermore the jaws of the clamp-type toggles cover areas of the leather which are thus prevented from receiving the tanning or drying action which is received by the remainder of the skin, while my clips permit the exposure of practically the entire area of the faces of the leather.

I claim:

1. Clip of the class described, comprising a piece of metal having a substantially flat body portion, a flange substantially at right angles thereto, a prong projecting upwardly from the flange and inclining toward the body portion, and a hook upon the body portion to secure the clip to a screen or the like, said flange providing a substantially straight edge.

2. Clip of the class described, comprising a piece of sheet metal having a substantially flat body portion, a flange substantially at right angles thereto, a prong projecting upwardly from the flange and inclining toward the body portion, and a tab upon the body portion to secure the clip to a board, screen or the like, said flange providing a substantially straight edge, an extension at the upper end of the body portion being bent out in the general direction of the flange to provide a finger hold.

3. Clip of the class described, comprising a piece of sheet metal having a substantially flat body portion, a flange substantially at right angles thereto, a prong projecting upwardly from the flange and inclining toward the body portion, and a tab upon the body portion to secure the clip to a screen or the

like, said flange providing a substantially straight edge, an extension at the upper end of the body portion being bent out and downwardly to provide an open hook for a finger hold.

4. A clip of the class described comprising a strip of sheet metal having a substantially flat body portion, a flange extending outwardly from the body portion, a prong struck out of the flange and inclined from the plane of the adjoining portion of the flange toward the body portion, and a tab struck out of the body portion and projecting from the body portion at the side thereof opposite said flange, said flange providing a substantially straight edge spaced outwardly from the base of said prong.

5. A clip of the class described comprising a strip of sheet metal having a substantially planar body portion, a flange extending outwardly from one end of the body portion, prongs struck up out of the flange and having a general inclination toward the body portion, said flange providing a substantially straight edge spaced outwardly of the bases of said prongs, said prongs being spaced at substantially equal distances from said edge of the flange, a tab struck out of the body portion of the clip and projecting from the same upon the side opposite that from which the flange projects and an upwardly curved extension upon the upper end of the body portion to afford a finger hold.

Signed by me at Salem, Massachusetts this 1st day of September 1932.

CORNELIUS J. CURRIER.
